UNITED STATES PATENT OFFICE.

FREDERICK A. KURSHEEDT, OF NEW YORK, N. Y.

DESIGN FOR A TRIMMING.

Specification forming part of Design No. 5,460, dated January 2, 1872.

SPECIFICATION.

To all whom it may concern:

Be it known that I, FREDERICK A. KURSHEEDT, of New York, in the county of New York and State of New York, have invented a certain new Design for a Dress-Trimming; and I do hereby declare that the following is a full, clear, and exact description thereof, reference being had to the accompanying drawing and to the letters of reference marked thereon which form a part of this specification.

The nature of my design is fully illustrated by the accompanying drawing, to which reference is made.

A represents a piece of plaiting, the plaits running diagonally, and having lace B or its equivalent sewed along its edges. On this plaiting, nearer one edge than the other, is

sewed a piece of fluting, C, with a narrow band or ribbon, D, stitched on the face to cover the raw edge of the fluting. This band may be of the same or different color from the plaiting and fluting, in either case forming a beautiful trimming for a variety of purposes.

What I claim is—

The design for trimming, as shown, consisting of the diagonal plaiting A, lace B, fluting C, and band D, as herein set forth.

In testimony that I claim the foregoing as my own I affix my signature in presence of two witnesses.

FRED. A. KURSHEEDT.

Witnesses:

JOHN A. DAVIS,
JAMES AULD.
